US00D848093S

(12) **United States Design Patent** (10) **Patent No.:** **US D848,093 S**
(45) **Date of Patent:** **** May 7, 2019**

(54) **HARD SURFACE CLEANING DEVICE**

(71) Applicant: **Unger Marketing International, LLC**,
Bridgeport, CT (US)

(72) Inventors: **James M. Buckley**, New Hartford, CT
(US); **Joseph K. Patterson**, Monroe,
CT (US); **Bryan Lee Roberts**,
Dormagen (DE)

(73) Assignee: **UNGER MARKETING
INTERNATIONAL, LLC**, Bridgeport,
CT (US)

(**) Term: **15 Years**

(21) Appl. No.: **29/581,237**

(22) Filed: **Oct. 17, 2016**

(51) LOC (11) Cl. **15-05**

(52) U.S. Cl.

USPC **D32/18**

(58) **Field of Classification Search**

(57) **CLAIM**

The ornamental design for a hard surface cleaning device, as shown and described.

DESCRIPTION

FIG. 1 is a front, top perspective view of a hard surface cleaning device showing our new design;

FIG. 2 is a rear, bottom perspective view thereof;

FIG. 3 is a left side view thereof;

FIG. 4 is a right side view thereof;

FIG. 5 is a rear view thereof;

FIG. 6 is a front view thereof;

FIG. 7 is a top view thereof; and,

FIG. 8 is a bottom view thereof.

The details shown in broken lines form no part of the claimed design.

1 Claim, 8 Drawing Sheets
